UNITED STATES PATENT OFFICE.

JOHN WENNERG AND OLE LINDSTROM, OF FERTILE, MINNESOTA.

AUTOMATIC WAGON-BRAKE.

SPECIFICATION forming part of Letters Patent No. 509,063, dated November 21, 1893.

Application filed December 6, 1892. Serial No. 454,230. (No model.)

To all whom it may concern:

Be it known that we, JOHN WENNERG and OLE LINDSTROM, both of Fertile, in the county of Polk and State of Minnesota, have invented 5 certain new and useful Improvements in Automatic Wagon-Brakes, of which the following is a specification.

Our invention relates to automatic wagon brakes and the object of the invention is to 10 provide a brake which will be operated by the back pressure transmitted through the neck-yoke and which, consequently, will be entirely automatic in its action.

To this end our invention consists in the 15 combination with the wheels and the axle, of the hounds, the pole, and levers, bearing brake-shoes, pivoted upon said hounds, said levers being arranged to be operated by a rod extending forward and connected with the 20 neck-yoke.

Our invention will be more readily understood by reference to the accompanying drawings, forming a part of this specification, in which—

25 Figure 1 is a plan showing the front wheels, hounds and tongue of a vehicle and automatic brake embodying our invention. Fig. 2 is a side elevation with one of the wheels removed. Fig. 3 is a rear elevation of the 30 same. Fig. 4 is a detailed view showing the means for locking the rod upon the tongue.

As shown in the drawings, 2, 2 represent the front wheels of a wagon or vehicle.

3, 4 and 5 represent the axle, the sandboard, 35 and the bolster, respectively.

The hounds 6 and the circle 7 are of the usual construction and the pole 8 is secured thereto in the usual manner, and an ordinary rubber iron is also provided. Behind the 40 wheels we provide the two short horizontal levers 10 and 11 provided with the brake-shoes 12 and having slotted inner ends which are connected by the bolt 13. On the back of the circle is the iron strap 14 secured thereto 45 in any suitable manner and having the back-wardly extending ends 15 provided with the curled ends 16 in which the pivot bolts 17 of the levers are secured. Short braces 18 extend between the angle ends 15 and the inner 50 part of the strap 14. These levers are nor-mally held in the position shown by the flat

pillow spring 19 having the ends 20 fastened upon the studs 21 projecting from the tops of the levers. The bow of the spring thus presses against the inner ends of both levers. From 55 the bolt 13 extends the brake rod 22, preferably formed in a loop bent about the king-bolt 23 and extending thence down to a point beneath the tongue where it is coupled by the hinged joint 25 to the rod 26 extending for- 60 ward to the tongue and having the shoulder 27 to be engaged by the ring 28 of the neck-yoke 29. It will be seen that when a back-ward pull is exerted upon the neck-yoke, as by the backing of the horses in going down 65 hill, the brake-rod will be forced backward against the pressure of the pillow spring 19 to straighten the levers and press the brake shoes against the wheels. The pressure ex- 70 ereted upon the draft-rod is greatly increased by the long leverage of the levers which as shown are pivoted near their outer ends.

It is often desired to back the wagon and in order that this may be done when the team is hitched thereto, and without applying the 75 brakes, we preferably flatten the rod 26 at 30 and provide therein the hole 31, which is nor-mally beneath a hole provided in the tongue. Before backing the team, the driver, by insert-ing the short bolt 32 through the hole in the 80 tongue and through the hole 31 in the rod, may lock the rod against movement, thereby locking the brake.

Having thus described our invention, we claim as new and desire to secure by Letters 85 Patent—

1. The combination, in an automatic brake, of the front wheels of the vehicle, with the axle 3, the circle 7, the strap 14 secured to said circle 7 and having sleeved ends 16, brace 90 18, the levers 10 and 11 pivoted on said ends 16 and pivotally connected, brake-shoes on said levers, a spring 19 for normally holding said levers and brake-shoes out of engage- 95 ment with said wheels, and automatic means for forcing said levers and brake-shoes into engagement with said wheels, as and for the purpose set forth.

2. The combination, in an automatic wagon 100 brake, of the front wheels of the vehicle, with the axle 3, the circle 7, the pole, the metal strap 14 secured to said circle 7 and having

curled ends 16, said ends 15 being strengthened by braces 18, the levers 10 and 11 pivoted on said ends 16 and having slotted ends, brake-shoes on said levers, a spring 19 for normally holding said levers and brake-shoes away from said wheels, and a rod 22 pivoted to the inner ends of said levers, a rod 26 connected with the rod 22 and extending along the pole to engagement with the neck-yoke, 10 as and for the purpose set forth.

3. The combination, with the front wheels, of the hounds and circle, the pole, short levers 10 and 11 pivoted on said circle and having brake shoes to engage said wheels, a bow-spring arranged on said levers, the neck-yoke, 15 and a rod extending therefrom to a pivotal connection with the inner ends of said levers, substantially as described and for the purpose specified.

4. The combination with the wheels, of the hounds and circle, the pole, brake levers mounted on said circle, means for normally holding the same out of engagement with the wheels, and a brake rod extending from said levers to the end of said pole, said rod provided with the hole 30, and the tongue with the corresponding hole, and a bolt 32 to be inserted therein to lock said rod and the brake, substantially as described.

In testimony whereof we have hereunto set 30 our hands this 28th day of November, A. D. 1892.

JOHN WENNERG.
OLE LINDSTROM.

In presence of—

A. NELSON,
E. L. JOHNSTON.
